COMBINED PROCESS FOR CONVERTING
LIGHT AND HEAVY HYDROCARBONSEdmund G. Borden, Little Neck, N. Y., assignor to
Cities Service Oil Company, New York, N. Y., a
corporation of Pennsylvania

Application November 17, 1938, Serial No. 241,031

9 Claims. (CL. 196—9)

This invention relates to a combined process for converting hydrocarbons such as normally gaseous hydrocarbons and liquid hydrocarbons into a gasoline-like product suitable for use in internal combustion engines.

Considerable progress has been made in the conservation of the low molecular weight hydrocarbons by polymerizing them into hydrocarbons suitable for motor fuels and other products, but no apparent attempt has been made to save the C₂ hydrocarbons, ethane and ethylene. The C₃ and C₄ hydrocarbons are recovered in some stabilizing operations and such hydrocarbons sent to a polymerization unit to be converted into higher boiling products.

The primary object of the present invention is the provision of an improved process for combining the polymerization of normally gaseous hydrocarbons such as C₂, C₃ and C₄ hydrocarbons with the conversion of oil cracking stocks.

A further object of the invention is to provide a combined conversion process which is particularly suited for the substantially complete conversion of various types of hydrocarbons into gasoline motor fuel.

In general the improved process of the present invention involves the steps of subjecting a heavy hydrocarbon to a cracking temperature in the vapor phase, the cracking of a normally gaseous hydrocarbon to convert it substantially to unsaturated constituents, the mixing of the hydrocarbons from these two conversion steps, and subjecting the resulting mixture to conditions for promoting polymerization and alkylation reactions for the production of a product containing a very high percentage of aromatic hydrocarbons. The improved process also includes the refining of the conversion products and particularly the recovery of the unconverted C₂, C₃ and C₄ hydrocarbons and the return of such hydrocarbons free of hydrogen and methane to the conversion operation.

Various other features, objects and advantages of the improved process of the present invention will be apparent to those skilled in the art from the following more detailed description of the invention taken in connection with the accompanying drawing in which:

The single figure is a conventional elevational diagram of an improved cracking unit particularly adapted for carrying out the process.

The heavy hydrocarbon material to be processed in accordance with the features of the invention and which may comprise crude oil, topped crude or other heavy petroleum oil, is introduced

into the apparatus shown in the drawing through a line 2 (lower left hand corner of the drawing) and forced by means of a pump 4 at a pressure of from 500 to 600 lbs. per square inch through a line 6 and a vaporizing coil 8 mounted in a pipe still furnace 10. The oil passing through the coil 8 is heated to a temperature of from 800° to 900° F., which is sufficient to vaporize substantially all of the constituents boiling within the gas-oil range as well as lower boiling hydrocarbons. The resulting heated hydrocarbon material is passed from the coil 8 through a line 12 into a vapor separator 14 in which vapors are separated from unvaporized oil constituents and conducted at a pressure of from 350 to 400 lbs. per square inch through a vapor line 16 and a cracking coil 18 mounted in the pipe still furnace 10. The relatively heavy hydrocarbon vapors introduced into the coil 18 are heated to a temperature of from 925° to 1050° F. and substantially cracked to produce a maximum of unsaturated hydrocarbons including some olefin gases of lower boiling point than gasoline. In this coil no attempt is made to convert the heavy hydrocarbon vapors to gasoline, but the temperatures for cracking are controlled to cause such a rearrangement or breaking of the hydrocarbon molecules that they will be prepared for a later cracking and polymerization reaction. The cracked products formed in the cracking coil 18 are conducted through a line 20 and passed into a polymerization furnace 22.

The light normally gaseous hydrocarbons to be converted in accordance with the features of the present invention are at least partially derived from the process and conducted through a line 23 at a pressure of from 400 to 550 lbs. per square inch into a heating coil 24 mounted in a pipe still furnace 25. In this furnace the normally gaseous hydrocarbons comprising substantially only C₂, C₃ and C₄ hydrocarbons are rapidly heated to a temperature of from 950° to 1200° F., to break up the saturated hydrocarbons and produce a maximum of olefins. Ordinarily it is not possible to obtain more than about 50% or 60% of olefins by thermal conversion in the coil 24. The highly heated hydrocarbon mixture is therefore conducted through a transfer line 26 into the lower portion of a catalytic chamber 27 where the heated hydrocarbons are brought in contact with a dehydrogenating catalyst such as chromic oxide or chromium trioxide which will give a mixture containing from 60% to 90% unsaturated hydrocarbons. This mixture of olefin hydrocarbons is conducted through a valved line 28 into

the line 20 and directly mixed with the high temperature cracked products from the cracking coil 18. If desired, any part or all of the highly heated gaseous hydrocarbons discharged from furnace 25 through the line 26 may be by-passed through a valved line 30 into the line 28 to mix with the unsaturated hydrocarbons from the reaction chamber 27.

The mixture of hydrocarbons from cracking coils 18 and 24, and which preferably comprises at least 50% by weight of normally gaseous hydrocarbons, is conducted into the polymerization furnace 22 and passed through a series of heating coils 32 arranged in parallel as illustrated diagrammatically in this furnace. The use of these parallel coils permits the maintenance of a relatively long time polymerization reaction without causing an excessive pressure drop through the heater. The resulting products are discharged from the coils 32, through a transfer line 34 at a temperature of from 1050° to 1075° F. and a pressure of approximately 225 lbs. per square inch, and they are conducted through a line 34 into the upper portion of an enlarged vertical reaction chamber 36 where the polymerization, alkylation and cracking reactions are continued at reduced velocity while the products pass downwardly through this chamber.

The dehydrogenation reaction which takes place in the chamber 27 may advantageously comprise the treatment of the hot gases with a catalytic material such as a mixture of magnesium oxide and chromium trioxide, or chromic oxide, or aluminum oxide and chromium oxide, and such oxides or mixtures of oxides may be deposited on fuller's earth and arranged in vertically spaced trays in the chamber 27. The gases are held at a temperature of from 1050° to 1200° F. as they emerge from the coil 24 and are preferably held at a temperature of approximately 1100° F. These gases are under the pressure maintained in the coil 24 which may vary from 300 to 450 pounds. It is economically desirable to maintain the same pressure in the chamber 27 as that existing at the outlet of the coil 24 and accordingly the temperature of the entering gases is maintained high in order to promote the reaction. The conversion of paraffins to olefins is more rapid under lower pressures, but in view of the fact that it is desirable to maintain the same pressure in chamber 27 as at the outlet of the coil the temperature is preferably increased to give the desired dehydrogenation reaction. If necessary the chamber 27 may be heated externally to maintain the desired temperature therein.

The unvaporized heavy hydrocarbon oil constituents separated out in the separator 14 are normally withdrawn through a valve line 37 and used as fuel oil. If the oil residue has not been subjected to cracking conditions for a sufficient period in coil 8 to properly break the viscosity of the heavy hydrocarbons, this oil is subjected to higher temperature cracking conditions. In this case the liquid material is withdrawn from the bottom of the separator 14 through line 37 and a valved line 38 and introduced into the mid-portion of the reaction chamber 36, so that the heavy hydrocarbons are brought into contact with the high temperature vapor and gas products introduced through the line 34. The resulting mixture of products pass downwardly through the chamber 36 and as the products approach the inlet to a funnel 40, they are substantially instantaneously reduced in temperature to a point below

that of coke deposition by intimate contact with a relatively cool fluid introduced through a spray nozzle 42. The fluid introduced through the nozzle 42 may be water but preferably oil, such as concentrator gas-oil or other heavy oil, supplied through a line 44. Where the viscosity of the heavy oil constituents collected in the bottom of the separator 14 is suitable for use as fuel oil this hydrocarbon material may be used in part as a quenching medium for the nozzle 42 by passing it through a valved connecting line 46.

The cooling effected in the lower portion of the reaction chamber 36 as the hot products enter the funnel 40 is preferably sufficient to condense substantially all hydrocarbons boiling above that of ordinary gas oil. Any such condensate together with the fuel oil constituents introduced into or formed in the chamber 36 are discharged with the uncondensed vapors through the funnel 40 into a separating chamber 48 and then conducted through a valved line 50 into a low pressure concentrator 52. A pressure of approximately 225 lbs. per square inch is maintained in the reaction chamber 36 and separator 48, so that considerable distillation may be effected in the concentrator 52 by reducing the pressure on the liquid oil constituents passing through the line 50. The vaporization however, is preferably controlled, so that a fuel oil of proper consistency will be obtained from the concentrator. This is withdrawn to storage through a valved line 54. The vapors produced in the concentrator pass through a vapor line 56, are condensed by a condenser mounted therein and collected in an accumulator 58 from which any uncondensed gas is discharged through a valve controlled gas line which is used to maintain the desired back pressure on the concentrator 52.

The vapors remaining uncondensed in the conversion operation and separated out in the chamber 48 are conducted through a vapor line 60 into a dephlegmator or fractionating tower 62. The vapors in the line 60 may be further cooled by introducing cooling fluid from the line 44 directly into the line 60 through a valved line 64, but the cooling should not be carried to such a low temperature that the gasoline boiling point material will not all be driven overhead from the tower 62. The vapors introduced from the line 60 into the lower part of the tower 62 are fractionated, and additional cooling may also be effected in the lower part of this tower by utilizing all or a portion of the distillate from the accumulator 58, this distillate being withdrawn from the accumulator through a line 66 and forced by means of a pump mounted therein through a valved connecting line 68 into the lower part of the tower 62 above the point of vapor introduction from the line 60. Vapors entering the tower will be brought in intimate contact with any of the distillate from the line 68 and vaporize any of the low boiling gasoline hydrocarbons which may be present in the distillate.

The fractionating operation carried out in the tower 62 is preferably controlled so that all high boiling material above the boiling point of gasoline will be condensed. This condensate, together with the distillate from the accumulator 58, and conducted through valved lines 66 or 68, is withdrawn from the tower through a line 70 and forced by means of the pump mounted therein into the line 6 through which it is supplied as charging stock for the vaporizing coil 8.

The gasoline boiling point vapors and uncon-

densable gases from the conversion operation are separated out in the tower 62 and are conducted through a vapor line 72, subjected to condensing conditions in a condenser mounted therein, and discharged into an accumulator 14 in which the uncondensed normally gaseous hydrocarbons are separated from the gasoline boiling range condensate. The gasoline collected in the accumulator 14 is withdrawn through a line 16 and forced by means of a pump mounted therein through a valved line 18 and a heat exchanger 80 mounted therein into the mid-portion of a stabilizer tower 82.

The gases separated out in the accumulator 14 comprise hydrogen, methane, the C₂, C₃, C₄ and some C₅ hydrocarbons which are produced in the conversion operation or remain unconverted therein. This mixture of gases is withdrawn from the accumulator 14 through a valved line 84 and placed under a pressure of about 600 lbs. per square inch by a compressor mounted therein, cooled in a cooler 86 and discharged into the lower portion of an absorber 88 where the gases are subjected to the absorbing action of a suitable absorption oil for the recovery of the C₂ and higher hydrocarbons substantially free of methane and hydrogen, the latter gases being discharged through a valved line 90. The cooling of the gases from the compressor in the cooler 86 may be effected at least in part by heat exchange with gasoline from the line 16 which may be conducted through the cooler in indirect heat exchange with the gases and back into the line 18, beyond the valve mounted therein, as shown.

The absorber 88 includes suitable means such as bubbler trays, for providing intimate contact between the gases and the absorption oil, and is also preferably provided with cooling coils to increase the absorption efficiency. The absorption oil used in the absorber 88 may be any oil from a gasoline range to a gas-oil boiling range, but it has been found that better absorption is obtained with the lower boiling oil. This oil is introduced into the absorber under pressure through a line 92, and the rich absorption oil is removed from the bottom of the absorber through a float valve controlled line 94, heated by a heater mounted therein and passed into a still 96 which is used for separating the absorbed normally gaseous hydrocarbons from the absorption oil. The rich absorption oil may be heated to a temperature sufficient to drive over any gasoline boiling range material absorbed from the gases and these vapors are passed through a valved vapor line 98 into the mid-portion of the stabilizer 82 above the point of introduction of the gasoline through the line 78. The lean absorption oil obtained in the still 96 is removed through a line 100, passed through the heat exchanger 80 to heat the gasoline in the line 78 and then forced by means of a pump mounted in the line 100 through a cooler 102 and a line 104 into the upper part of the absorber 88. If a gasoline boiling range absorption oil such as a stabilized gasoline or a heavy gasoline is used as the absorption medium in the absorber 88, the rich absorption oil is preferably conducted directly into the stabilizer 82 and subjected to rectification therein along with the unstable gasoline from the accumulator 14.

The pressure in the absorber 88 is preferably maintained at from 500 to 600 lbs. per square inch and that in the still 96 at a slightly lower pressure, such that the pressure in the stabilizer 82 may be maintained in the neighborhood of

500 lbs. per square inch. In the operation of the absorber 88 the gases removed overhead through the line 90 in addition to hydrogen and methane may include nitrogen and also some carbon oxygen gases in addition to a small proportion of C₂ hydrocarbons. However, the operation is preferably controlled so that as much as possible of the C₂ hydrocarbons will be absorbed. Under the pressure conditions referred to, the rich absorption oil will be heated to a temperature of from 500 to 700° F. in the heater mounted in line 94.

The stabilizer 82 is operated as a rectification column to produce a bottom product comprising stabilized gasoline having the desired vapor pressure and containing the requisite proportion of C₄ hydrocarbons to give this vapor pressure. The excess of the C₄ hydrocarbons and the C₂ and C₃ hydrocarbons are removed over head from the stabilizer through a vapor line 106, passed through a condenser mounted therein, and the resulting condensate collected in an accumulator 108. Any uncondensable gases separated out in the accumulator 108 are withdrawn through a line 110 and placed under a pressure of about 600 lbs. per square inch by means of a compressor mounted therein, and passed to the absorber 88 through the line 84. The condensate collected in the accumulator 108 and comprising ethane, propane and butane and the corresponding unsaturated hydrocarbons, is withdrawn through a valved line 112 into a line 114, from which a suitable part of the condensate is forced by means of a pump 116 and a line 118 into the upper part 30 of the stabilizer 82, to provide a suitable reflux ratio in the top of the stabilizer. The net production of condensate in the accumulator 108 is conducted from the line 114 into the line 23 at a pressure of from 400 to 450 lbs. per square inch and passed directly to the heating coil 24 by the high pressure maintained in the stabilizer 82 and accumulator 108. The stabilized gasoline produced in the stabilizer 82 is withdrawn through a float valve controlled line 120.

45 While there will be considerable production of C₂, C₃ and C₄ hydrocarbon from the heavy hydrocarbon oil converted in the process, it has been found necessary to introduce additional hydrocarbons of this type to supply sufficient 50 charging stock for the furnace 25. This additional stock in the form of gaseous or liquefied ethane, propane or butane, or a mixture of any 55 of these hydrocarbons is introduced under a suitable pressure into the line 23 through a valved supply line 122. The necessity for using outside stock in the furnace 25 will be apparent from the fact that at least 50% of the material entering the furnace 22 is preferably derived from the furnace 25.

60 In place of the catalytic chamber 27 for the production of unsaturated gaseous hydrocarbons from the C₂, C₃ and C₄ hydrocarbons, particularly the production of olefins, a modified form of the pipe still 24 may be used. This dehydrogenation of the saturated hydrocarbons may be 65 accomplished by using a relatively small proportion of air or oxygen in treating the hydrocarbon vapors. To utilize the air for promoting a dehydrogenation reaction as distinguished from an oxidation reaction, the air must be mixed with the hydrocarbons in comparatively small increments and is preferably introduced into the tubes of the coil 24, after the hydrocarbon vapors have reached a predetermined temperature, in

comparatively small amounts. To accomplish this the air is introduced into the vapor stream through small tubes which project into the tubes of the coil 24. These small tubes are made of nickel or alloy metals and have porous walls through which air in minute streams is forced into the vapor stream by a comparatively high pressure. As shown in the drawing, air is forced by means of a pump 124 through a line 126 which is connected with a plurality of small tubes 128 which project into the tubes of the pipe coil 24 and terminate therein with porous tubular extensions for diffusing the air or oxygen into the vapor stream. By gauging the porosity of the tubes projecting into tubes of coil 24 and the pressure of the air in the line 126 any desired amount of air may be introduced into the coil for promoting the dehydrogenation reaction. The air emerges through the walls of the tubular extensions in minute streams and immediately reacts with the highly heated hydrocarbons. The small porous tubes extend for a considerable distance into the tubes of the pipe coil so that the air is distributed over a considerable area into the hydrocarbons. It is important that small proportions of air shall be used because the introduction of air promotes an exothermic reaction within the body of hydrocarbons which tends to raise the temperature. The temperature of the vapors preferably is held sufficiently high so that the oxygen unites with hydrogen to form steam, and oxidation of the hydrocarbons to produce alcohols, aldehydes, ketones and acids is avoided as much as possible. Some oxygen unites with carbon to form carbon monoxide but this gas is not objectionable.

The polymerization reactions carried out in the furnace 22 and the enlarged reaction chamber 36 are preferably controlled to obtain a rather long time moderate temperature polymerizing action which favors the production of aromatic hydrocarbons. Such polymerization reactions may be substantially exothermic and result in the production of a gasoline boiling range product containing from 65% to 95% of aromatic hydrocarbons. The relatively low polymerizing temperatures promotes the formation of side chain benzene derivatives in which the side chains contain from four to seven carbon atoms. When the operation is controlled to produce such high percentages of aromatic hydrocarbons a relatively large proportion of fixed gas is produced which is composed mainly of hydrogen, methane and C₂ hydrocarbons.

It is not necessary however that the process be operated for the production of such high percentages of aromatic hydrocarbons since motor fuels containing from 25% to 60% are entirely satisfactory from the standpoint of fuel value and antiknock properties. When producing motor fuels of this character the gas production is much lower and will of course contain a greater proportion of unconverted C₂, C₃ and C₄ hydrocarbons which will be recycled in accordance with the above outlined process.

Having thus described the invention in its preferred form, what is claimed as new is:

1. In the conversion of relatively light oils into gasoline of relatively high anti-knock value in which C₂, C₃ and C₄ hydrocarbons remain unconverted in the operation and are also produced therein, the improvement which comprises fractionating the gasoline and lower boiling constituents of the conversion products of the operation from higher boiling hydrocarbons, subjecting

the gasoline vapors and lower boiling constituents to condensing conditions at a pressure of approximately 200-250 lbs. per square inch to condense the gasoline constituents, separating the resulting condensate from uncondensed gases comprising hydrogen, methane, C₂, C₃, C₄ hydrocarbons, passing the separated gases through an absorption zone in intimate contact with a cool absorption oil and absorbing the C₂, C₃ and C₄ hydrocarbons therein at a pressure in excess of 500 lbs. per square inch, passing the rich absorption oil into a still and vaporizing the C₂, C₃ and C₄ hydrocarbons from the absorption oil by heat, passing the resulting vapors as such and also the gasoline condensate produced by said condensation into the mid-portion of a high pressure stabilizer maintained at a pressure of approximately 500 lbs. per square inch, fractionating the gasoline and gases in said stabilizer to produce a stabilized gasoline having the desired vapor pressure and an overhead fractional condensate comprising a mixture of C₂, C₃ and C₄ hydrocarbons at a pressure of approximately 500 lbs. per square inch, passing said mixture by means of said pressure thereon to a conversion zone and subjecting it therein to a rapid thermal conversion operation to convert said hydrocarbons into a product containing a substantial proportion of olefins and alkyl radicals, and thereafter polymerizing the resulting products with highly heated substantially cracked oil in a polymerization and alkylation zone for the production of said conversion products referred to.

2. In the conversion of relatively light oils as defined in claim 1 in which said mixture of C₂, C₃, and C₄ hydrocarbons subjected to rapid cracking conditions for the production of olefins are also subjected to the action of a dehydrogenating agent to materially increase the production of unsaturated hydrocarbons and alkyl radicals, and thereafter passing the resulting mixture containing in excess of 60 percent of unsaturated hydrocarbons into said polymerization zone.

3. In the conversion of hydrocarbons into gasoline in which C₂, C₃ and C₄ hydrocarbons remain unconverted in the operation and are also produced therein, the improvement which comprises separating the gasoline and lower boiling constituents of the conversion products of the operation from higher boiling hydrocarbons by fractionation, subjecting the gasoline vapors and lower boiling constituents to condensing conditions at a pressure of approximately from 200 to 250 lbs. per square inch to condense the gasoline constituents, separating the resulting condensate from uncondensed gases comprising hydrogen, methane, C₂, C₃, and C₄ hydrocarbons, compressing the separated uncondensed gases to a high pressure of approximately 500 lbs. per square inch and passing them in indirect heat exchange with said gasoline condensate to cool the gases, thereafter passing the cooled gases into an absorption zone in intimate contact with a cool absorption oil, and absorbing the C₂, C₃ and C₄ hydrocarbons therein at a pressure of approximately 500 lbs. per square inch, passing the resulting rich absorption oil from said absorption zone into a still and vaporizing the C₂, C₃ and C₄ hydrocarbons from the absorption oil by heating the same, passing the resulting vapors as such and also the gasoline condensate produced by said condensation after said heat exchange with said uncondensed gases into the mid-portion of a high pressure stabilizer maintained at a pressure of approximately 500 lbs. per square inch, fractionating the gasoline

and vapors from said still in said stabilizer to produce a stabilized gasoline having the desired vapor pressure and an overhead fractional condensate comprising a mixture of C₂, C₃ and C₄ hydrocarbons at a pressure of approximately 500 lbs. per square inch, and passing the hot absorption oil from said still in indirect heat exchange with said gasoline immediately prior to the introduction of the gasoline into said stabilizer.

4. The process of converting hydrocarbons into a product boiling within the gasoline range and containing in excess of 60% aromatic hydrocarbons, which comprises separately and simultaneously heating and cracking a high boiling hydrocarbon oil and a mixture of C₂, C₃, and C₄ hydrocarbons while passing them in restricted streams through heating zones, heating the heavy hydrocarbon to a temperature of approximately 950° F. to convert the same into unsaturated hydrocarbons, heating said mixture to a temperature of approximately 1100° F. to produce a high percentage of unsaturated hydrocarbons, immediately mixing the highly heated products from said heating zones and passing the resulting mixture in a stream of restricted cross section through a further heating and polymerization zone in which the products are inter-polymerized and converted into aromatic hydrocarbons, cooling and fractionating the resulting conversion products to produce a vapor and gaseous fraction comprising the gasoline and lower boiling hydrocarbons and gases, subjecting this vapor mixture to condensing conditions at a pressure of approximately 200 to 250 lbs. per square inch to condense the gasoline hydrocarbons, separating the uncondensable gases from the gasoline condensate and compressing the gases to a high pressure of at least 500 lbs. per square inch, passing the resulting compressed gases into an absorber in intimate contact with an absorption oil and absorbing the C₂, C₃, and C₄ hydrocarbons from the compressed gases, passing the rich absorption oil into a still and vaporizing the absorbed constituents by heat, passing the resulting vaporized constituents as such and also said separated gasoline condensate into the mid-portion of a stabilizer in which fractionation of the gasoline and introduced

constituents is effected at a pressure of approximately 500 lbs. per square inch to produce a stabilized gasoline of desired vapor pressure and an overhead condensate comprising C₂, C₃, and C₄ hydrocarbons, and supplying said overhead condensate directly at a pressure of approximately 500 lbs. per square inch as at least a part of the said mixture heated in one of said heating zones.

10 5. The process of conversion as defined by claim 4 in which said separated gasoline is first passed in heat exchange with said compressed gases, then in indirect heat exchange with hot absorption oil withdrawn from said still, and finally introduced into said stabilizer.

15 6. The process as defined by claim 4 in which said overhead fractional condensate is produced at a pressure of approximately 500 lbs. per square inch and conducted directly without further compression into the heating zone for said mixture of C₂, C₃, and C₄ hydrocarbons.

20 7. The conversion process as defined by claim 4 in which the highly heated mixture of C₂, C₃, and C₄ hydrocarbons is subjected to active dehydrogenation with a dehydrogenating agent prior to its mixture with the highly heated high boiling hydrocarbons.

25 8. In the conversion of C₂, C₃, and C₄ hydrocarbons as defined in claim 1 in which said gases are subjected to a high decomposing temperature of from 1000° to 1200° F. by an indirect heating of the gas and the introduction of air in small proportions into the gas to promote the production of unsaturated hydrocarbons therein and passing said unsaturated gases into the polymerization and alkylation zone.

30 9. In the conversion of C₂, C₃ and C₄ hydrocarbons as defined in claim 1 in which said hydrocarbon mixture is subjected to high temperatures by indirect heating and introducing air in minute quantities at a plurality of points in the path of travel of the hydrocarbons to promote an exothermic reaction in the hydrocarbon mixture for the production of unsaturated hydrocarbons and alkyl groups and passing said preheated and oxidized mixture into the polymerization zone.
